UNITED STATES PATENT OFFICE.

ALDO M. FRANCHI, OF NEW YORK, N. Y., ASSIGNOR TO FRANCHI RINGLESS PISTON CORPORATION, OF NEW YORK, N. Y., A CORPORATION OF NEW YORK.

PISTON.

Application filed January 18, 1923. Serial No. 613,386.

To all whom it may concern:

Be it known that I, ALDO M. FRANCHI, a citizen of the United States, and resident of the city of New York, in the county of New York and State of New York, have invented certain new and useful Improvements in Pistons, of which the following is a specification.

The present invention relates to improvements in pistons, and more particularly to trunk pistons, especially designed for use with internal combustion engines.

The main object of the invention is to provide a simple, inexpensive and durable piston rod connection, wherein wearing of the elements is compensated, lost motion of the piston being thus precluded.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:—

Figure 1 is a central vertical section taken through a piston constructed in accordance with the present invention; Fig. 2 is a top plan view of one of the elements of the piston rod connecting means; Fig. 3 is a front elevation of the said element; and Fig. 4 is a top plan view of a spring element co-operating with the element shown in Figs. 2 and 3.

In the drawings, the numeral 10 indicates a trunk piston, including a cylindrical shell 11, which is open at one of its ends and closed at its opposite end by a head 12. From this head extends centrally downwards into the shell a hollow boss 13, strengthened by ribs 15 and provided with a reduced cylindrical exteriorly screw-threaded lower portion 16. With the threads of this portion mesh the interior threads of a sleeve 17, which is provided upon its free lower end with an inwardly

extending annular shoulder 18. In the boss 13 is formed, above its screw-threaded portion, an interior annular shoulder 19, against which abuts a bearing cup 20, with which co-operates a ring-shaped bearing member 21. The cup and this bearing member constitute a spherical socket, into which is fitted the spherical head 22 of a piston rod 23. The bearing member 21 is shiftably mounted in the sleeve 17, it being substantially wedge-shaped, its underface extending in a plane at an angle to the longitudinal axis of the piston shell. With this wedge-shaped bearing member co-operates a split ring 24, which rests upon the annular shoulder 18 of the sleeve 17, it being adapted to slide on the said shoulder laterally. This split ring is also wedge-shaped, its upper face bearing against the lower face of the bearing member 21 throughout its entire area. From the foregoing and from an inspection of Fig. 1 of the drawings it appears that the bearing member 21 and the split ring 24 taper in opposite directions, whereby, when the split ring 24 is shifted laterally in the direction of the arrow shown in Fig. 1 of the drawings, the bearing member 21 is shifted in the direction of the longitudinal axis of the piston shell. For holding the upper face of the split ring 24 continuously in contact with the underface of the bearing member 21, there is a spring 25 provided. This spring is made in the form of an open ring, encircling the sleeve 17. One of the ends of this ring, denoted by the numeral 26, is bent inwards toward the center of the ring and extends through a slot 27 in the sleeve 17 into a recess 28 in the split ring 24. This recess is formed in the thickest portion of the split ring, as clearly appears from Figs. 1 and 3 of the drawings. The ring 24 is split to allow of a proper assembling of the elements.

The upper end of the sleeve 17 is provided with a flaring skirt 29, in which oil collects as the piston is operated in its cylinder. The oil flows from this skirt through the registering apertures 30 and 31 in the reduced portion 16 of the boss 13 and the bearing cup 20, respectively, and through a bore 32 in the said bearing cup to the spherical head 22 of the piston rod, whereby proper lubrication of the bearing cup, bearing member 21 and spherical head 22 of the piston rod is obtained.

The operation of the device is as follows: If the head 22 of the piston rod or the cup 19 and bearing member 21 wear, the spring 25 causes the wedge-shaped ring 24 to move laterally on the shoulder 18, thereby shifting the bearing member 21 in the direction of the longitudinal axis of the shell 11 of the piston, to compensate for the wear. Lost motion of the elements is thus prevented. It is to be noted that the spring 25 at the same time prevents turning of the bearing member 21.

What I claim is:—

1. The combination with a trunk piston 15 having a boss projecting downwards from its head into its shell provided with a cylindrical portion having exterior screw-threads, of a sleeve having interior screw-threads meshing with those of said cylindrical portion 20 provided at its free end with an annular inwardly projecting shoulder, a spherical socket comprising a stationary member within said cylindrical portion and a movable member within said sleeve, a piston rod 25 projecting into said sleeve having a spherical head seated in said socket, the movable member of said socket being wedge-shaped and shiftable within said sleeve in the direction of the longitudinal axis of said piston 30 shell, a wedge-shaped ring shiftable laterally on said shoulder and abutting against said movable socket member, said sleeve being provided with a slot in alignment with

a recess in said ring, and a ring-shaped spring surrounding said sleeve having spaced apart ends, one of said ends being bent radially inwards and extending through said slot into said recess to shift said ring laterally so as to cause movement of said movable socket member in the direction of the longitudinal axis of said sleeve, whereby wear of said socket members and the spherical head of said piston rod is compensated. 35

2. In a ball and socket joint, the combination with a sleeve, of two socket members therein, one of said socket members being fixed and the other movable in the direction of the longitudinal axis in said sleeve, a ball member seated in said socket members, said movable socket member being wedge-shaped, a wedge-shaped member movable laterally within said sleeve and abutting against said movable socket member, and a ring-shaped spring surrounding said sleeve having spaced apart ends, one of said ends being bent radially inwards and extending through said sleeve into engagement with said laterally movable member to shift the latter laterally so as to cause movement of said movable socket member in the direction of the longitudinal axis of said sleeve. 40 45 50 55 60

Signed at New York, in the county of New York and State of New York, this 18th day of October, A. D. 1922.

ALDO M. FRANCHI.
